INDICATING MEANS

Filed Nov. 16. 1926

INVENTOR
B. F. Huches, Jr.
ATTORNEY
John O. Seifert

UNITED STATES PATENT OFFICE.

BENJAMIN F. HUTCHES, JR., OF ALLENDALE, NEW JERSEY.

INDICATING MEANS.

Application filed November 16, 1926. Serial No. 148,633.

This invention relates to time indicating means particularly adapted for use in motor vehicles for ascertaining the elapsed parking time of a vehicle, although it is also adapted for other purposes, and it is the object of the invention to provide an indicating device for this purpose which is novel, cheap to manufacture and efficient in use.

10 A further object of the invention is to provide a time indicating device for this purpose and a bracket to adjustably mount the same, as upon the door of a motor vehicle, whereby when the device has been 15 adjusted for use the same may be readily observed, and when not in use may be adjusted into the bracket and out of sight.

In carrying out the invention there is provided a casing arranged with a clock dial 20 and concentrically mounted hour and minute indicating hands movable relative to said dial and co-operating therewith to indicate time, means for adjusting or setting said hands, and means to make said adjusting 25 means impossible of manipulation by an unAUTHORIZED person, and provide a bracket arranged for the adjustable mounting of said device therein whereby it may be readily observed when in one adjusted 30 position upon the bracket and out of view in another position thereof.

In the drawing accompanying and forming a part of this specification Figure 1 is a front elevation of an embodiment of my 35 improved indicating device and showing the same mounted in a supporting bracket therefor.

Figure 2 is a view looking at the rear of Figure 1 with the casing partly broken away 40 to show the operative connection of the hour and minute hands and the means for adjusting or setting the same in inoperative position and locked in such condition.

Figure 3 is a sectional view taken substantially central through Figure 2 and looking toward the right thereof.

Figure 4 is a sectional detail view of the hand setting means and showing the means for rendering the same inoperative adjusted 50 to position to permit actuation of said means for setting the hands.

Figure 5 is a detail view, partly in section, of means for releasably retaining the device in the bracket in the adjusted position shown in Figures 1 to 3.

Figure 6 is a sectional side elevation show-

ing a modified construction and arrangement of my improved indicating device and showing the same adjusted to operative position in a supporting bracket therefor; and 60

Figure 7 is a front elevation on a reduced scale of the device shown in Figure 6.

In carrying out the embodiment of the invention shown in Figures 1 to 5 there is provided a casing, which may be of the conventional watch case form, including a body 8 with a crystal carrying front 9 and a back 10, with a dial 11, such as a clock dial, mounted in the casing below the crystal, said dial being calibrated in the usual manner to indicate twelve hours of time with the spaces between the hour indications divided to read and indicate five minutes. A hand or pointer 12, to constitute the minute hand, is mounted on one end of an arbor in the 70 form of a sleeve 13 extending centrally through the dial with the hand arranged in juxtaposed relation to the front of the dial, said arbor being rotatably mounted in a frame (designated in a general way by F) 75 in the casing. A hand or pointer 14, to constitute the hour hand, is mounted concentrically relatively to the minute hand for revolute movement about the dial in juxtaposed relation to the minute hand by engaging the same upon the end of a shaft 15 rotatably supported in the arbor 13. The hands are geared together to revolve the hands about the dial by the movement of one of the hands in the ratio of one revolution of the hour hand to twelve revolutions of the minute hand. For this purpose a gear 16 fixed to the arbor meshes with a 80 pinion 17 fixed to a shaft 18 rotatably mounted in the framework, and a gear 19 on 85 said latter shaft meshes with a pinion 20 fixed to the shaft 15 carrying the hour hand. To actuate the gearing to revolve the hands, a pinion 21 fixed to or integral with the arbor 13 meshes with a pinion 22 fixed to a 90 shaft 23 mounted in ears stamped from the framework, as at 24, to rotate on an axis transverse to the axis of the pinion 21, said shaft also having a pinion 25 fixed thereon. A stem in the form of a shaft 26 is mounted 95 in a bearing 27 in the casing wall to have axial sliding and rotative movement on an axis parallel to the axis of shaft 23, with a knurled head 28 fixed to an end of the shaft exterior of the casing and said head embracing and having sliding movement 100 with the shaft relative to a sleeve 29 car-

ried at one end by the casing and enclosing the shaft 26 and its bearing. The stem carries a pinion 30 thereon within the casing to mesh with the pinion 25 and by the rotation of which pinion with the shaft the hands are revolved through the pinion 25. The stem is normally urged to position with the pinion 30 carried thereby out of mesh with the pinion 25 as shown in Figures 2 and 3 by a spring 31 coiled about the shaft 26 and confined between the bearing 27 and head 28. To operatively connect the stem with the pinion 25 to set the hands relative to the dial axial inward movement is imparted to the stem thereby throwing the pinion 30 into mesh with the pinion 25 and as the stem is rotated rotative movement is imparted to the pinion 25 and thereby the hands revolved about the dial.

As stated, the device is particularly adapted for ascertaining the elapsed time of the parking of a motor vehicle. For this purpose the hands are set to correspond with the time when the vehicle is parked to indicate the commencement of the time the vehicle was parked, the parking time or period being ascertained by the time indication to which the hands are set and comparing the same with the time indicated by a watch or clock.

To prevent tampering with and unauthorized setting of the hands means are provided to render the setting stem inoperative or lock the same in its inoperative position with the pinion 30 carried thereby out of mesh with the pinion 25. For this purpose a rod 32 is carried by a bracket 33 fixed to the frame to have rotative movement on an axis transverse to the axis of the stem, as by arranging a screw thread on a portion of the rod for threaded connection with ears extending from the bracket, as shown at 34. One end of the rod is extended or bent laterally substantially at a right angle, as at 35, and arranged in the plane of axial movement of the stem, said extended portion being in the nature of an abutment to be moved into the path and extend longitudinally of the plane of movement of the stem and to be engaged by the end of the stem to prevent axial inward movement thereof against the action of the spring 31 and with the pinion 30 out of mesh with the pinion 25 as shown in Figure 4. While the stem may be rotated in this position it is incapable of having axial movement imparted thereto to throw the pinion 30 into mesh with the pinion 25. To render the stem operative the rod is adjusted so that the projection 35 will extend laterally of the path of the axial movement of the stem, as shown in Figure 2. To rotatably adjust the rod the end opposite to the projection 35 is arranged in line with an opening 36 in the casing and has a transverse slot therein for the engage-

ment of a key or the like inserted into said opening.

In the use of the device with motor vehicles it is preferably mounted upon the door, and particularly when used with vehicles having closed bodies, for observation through the door window. For this purpose the device is adjustably mounted in a bracket 38 fixed to the vehicle door in which the device is pivotally mounted, as at 39, the bracket being so arranged that as the device is adjusted to one position, as shown in Figures 1 to 3, the front of the device will extend above the lower portion of the window frame for observation through the door window, and releasably retained in such position by a spring influenced detent, as shown at 40 in Figure 5. In another position of the device it is swung on its pivot support 39 in the bracket in a direction toward the left as viewed in Figure 3 to suspend the device from its pivot support so that the parts shown uppermost in Figure 3 will be lowermost, and in which position the device will be out of view through the window.

In the embodiment shown in Figures 6 and 7 there is provided a cup shaped casing 41 of rectangular form, although it may be of circular or other desired form. The dial 11 is mounted on one face of a plate 42 which serves as a mounting frame for the concentrically arranged arbor 13 and shaft 15 and for the rotatable mounting of the intermediate pinion 17 and gear 19, said latter pinion and gear being rotatably supported upon a headed and shouldered stud 43 fixed in the plate. The plate is arranged with a flange 44 to lie in contiguous relation to the side wall of the casing to hold the same against canting movement and limit the movement of the same into the casing by engaging with the bottom thereof whereby the plate or frame in conjunction with the casing serves to enclose the hand operating gearing. The end of the shaft 15 opposite to that carrying the hand is extended and reduced and has a bearing in the bottom of the casing, as at 45. In this arrangement the hour hand 14 is mounted on the arbor 13 while a minute hand 12 is mounted on the shaft 15. To actuate the gearing to set the hands relative to the dial the shaft 15 is extended forwardly of the hand and has a knurled head 46 fixed thereto. To render the hands impossible of manipulation to set the same by an unauthorized person the casing is extended beyond the dial and hands and is closed by a crystal carrying frame 46 pivotally mounted on the casing, as at 47. The crystal carrying frame is releasably secured in casing closing position by a hasp 48 pivotally connected to said frame carrying a staple or keeper 49 for engagement in an opening in the casing wall and the casing of a key operated lock 50 mounted within the

casing 41 for the engagement of the bolt of said lock. A bracket 38' is provided for mounting the device for the purpose set forth in connection with the embodiment shown in Figures 1 to 3, the device being mounted in the bracket by extending the hinge pin for connecting the crystal carrying frame 46 with the casing beyond the casing and engaging said extended ends in ears 51 extending laterally of the bracket, these ears being arranged to also embrace opposite side portions of the casing when the device is adjusted to the position shown in Figure 6, and adapted to be sprung laterally by the passage between the ears of pins 53 fixed in and projecting laterally from the casing and which pins are adapted to engage upon said extended portion of the ears when the device is adjusted to the position shown in 20 said figure.

In the arrangement of Figures 1 to 3 the device may be provided with means to suspend the device instead of mounting it in a bracket, which means may comprise a split ring 51 carried by the sleeve 29 for the attachment of a suspending chain or cord. The dial may have a suitable indication thereon, such as the word "Parked" to give notice to an observer that the time indicated by the setting of the hands relative to dial 25 is the time of the beginning of the parking period of the car.

Variations may be made in construction and arrangement of parts, and portions of the invention may be used without others and come within the scope of the invention.

Having thus described my invention I claim:

1. In a time indicating device, a casing 40 arranged with a dial calibrated for hours and minutes, concentrically rotatable hour and minute hands mounted centrally of the dial and one rotatable from the rotation of the other, means for setting said hands relative to the dial normally out of operative relation therewith and adapted to be moved into operative connection therewith, and means operative independently of and co-operating with the setting means to positively lock said setting means in inoperative position.

2. In a time indicating device, a casing arranged with a clock dial, hour and minute hands mounted concentrically in the cas-

ing centrally of the dial for movement relative thereto, gearing for operatively connecting and rotating the hands one from the other, means for actuating said gearing from the exterior of the casing and thereby set the hands relative to the dial, said means being normally out of operative connection with the gearing and adapted to be moved into operative connection therewith, and means operative independent of the gearing actuating means of the hand setting means for locking said actuating means in inoperative position.

3. In a time indicating device as claimed in claim 2, wherein the actuating means for the hand operating gearing embodies a stem 70 mounted in the casing to have axial and rotative movement and having a part extending to the exterior of the casing with means thereon for imparting rotary and axial movement thereto, and the means for locking said actuating means in inoperative position comprising an abutment adapted to be moved into and out of the path of the axial movement of said stem.

4. In a time indicating device, a casing, a 80 clock dial mounted in the casing for visual observation, hour and minute hands mounted concentrically in the casing centrally of the dial for movement relative thereto, gearing for operatively connecting and rotating the 85 one hand from the rotation of the other hand, a stem mounted in the casing to have axial and rotative movement and having a part extending to the exterior of the casing with means thereon for imparting axial and 90 rotary movement thereto, and means to lock the axially movable stem in position with the gear thereon out of mesh with the pinion of the hand operating gearing comprising a 95 rod mounted in the casing for rotation on an axis transverse to the axis of the stem with one end of the rod bent laterally and adapted to be moved into and out of the path of the axial movement of the stem by the rotation of the rod, and the opposite end of the rod 100 arranged in line with an opening in the casing and having a slot therein for the engagement of a key inserted in the casing opening to rotate the rod.

Signed at the city of New York in the 105 county of New York and State of New York this 12th day of November, 1926.

BENJAMIN F. HUTCHES, JR.
